ATTORNEY.

UNITED STATES PATENT OFFICE.

FRANCIS A. PHELPS, OF BALTIMORE, MARYLAND.

DESIGN FOR A SPOOL-HOLDER BOX.

SPECIFICATION forming part of Design No. 23,750, dated October 30, 1894.

Application filed August 9, 1894. Serial No. 519,880. Term of patent 7 years.

To all whom it may concern:

Be it known that I, FRANCIS A. PHELPS, a citizen of the United States, residing at Baltimore, in the State of Maryland, have invented and produced a new and original Design for a Box, of which the following is a specification.

The design is shown in the accompanying drawing, the figure being a perspective view of the box.

The box, A, has an exterior tapering shape or outline, being wider at the one end, b, than at the other end, b', and its two long sides, c, taper or converge from said wide end toward the narrow end.

A ledge, d, extends continuously around the top of the box and incloses a top panel, e, having along its center an ornamental bar, f, consisting of alternate straight and circular sections.

A series of ornamental knobs, g, arranged in a straight row project from the side of the box.

What I claim is—

The design for a box, A, having two long sides tapered or converging toward one end, and also having a ledge, d, extending continuously around its top and inclosing a top panel, e, with a center ornamental bar, f, consisting of alternate straight and circular sections, and the long tapered sides of the box having a series of projecting knobs, g, arranged in a straight row, as herein shown and described.

In testimony whereof I affix my signature in the presence of two witnesses.

FRANCIS A. PHELPS.
